AIR BLAST MEANS FOR BUCKLE-TYPE BLANK FOLDING MACHINES

John A. McGarvey, Willow Grove, and Jules R. Adamick, Philadelphia, Pa.

Application June 11, 1952, Serial No. 292,959

1 Claim. (Cl. 270—68)

This invention relates to a blank folding machine, and more particularly concerns a machine and method for producing a gate folded blank with the gates tucked in.

While machines have been devised and are currently in use for producing blanks by buckle folding, such machines have not been entirely satisfactory for producing gate folded blanks with the gates tucked in. It has heretofore been difficult, in folding the body portion of a blank which has gates at both ends, to form a buckle. Machines that have been devised for this purpose have usually required more than one processing step to form the desired folds and to arrange the gates in the desired manner. It is one object of this invention to provide a method and apparatus overcoming the disadvantages discussed above.

It is another object of this invention to provide a relatively simple folding machine for forming a blank which is gate folded with the gates tucked in. Another object is to provide a buckle folding machine which forms a fold dividing the body portion of the blank into two parts and concurrently tucks the gates into the fold between the two parts.

Other objects and advantages of the invention, including the simplicity and economy of the same, as well as the ease with which it may be adapted for the formation of folded blanks of different types, will further become apparent from the description which follows and from the drawings, whereof:

Fig. 1 represents a view in side elevation, with certain parts broken away and others shown in section, of a buckle folding machine which embodies features of this invention;

Fig. 2 represents a view in perspective of a gate folded blank, with the gates tucked in;

Fig. 3 represents an enlarged side elevation of a portion of the apparatus shown in Fig. 1, with parts shown in section; and

Figs. 4, 5 and 6 represent enlarged views of the central portion of the device shown in Fig. 3, illustrating how the body portion of the blank is folded and how the ends of the gates are tucked in as the fold is formed.

Turning now to the specific embodiment of the invention selected for illustration in the drawings, the apparatus is particularly adapted to form a blank of the character illustrated in Fig. 2 which has a body portion comprising two panels A, A, said body portion having a central fold B. The blank also includes integral gates C, C' which are folded with respect to body portion A along the fold lines D, E. The gates have free end edges F, F' which are adjacent to the fold line B and adjacent to one another. The blank in Fig. 2 is shown partially un-folded for the sake of clarity. To complete the fold the edges D, E would simply be brought toward one another bookwise to establish face to face contact between the gates C, C'.

Turning now to Fig. 1, the number 10 designates a roller which is mounted on a shaft 11 journaled in a pair of roller brackets 12 each of which is pivoted to a bracket shaft 13. The roller 10 is readily adjustable through an arc about the pivot 13 by an adjuster screw 14 which has a bottom head 15. A collar 16 is fixed by means of set screw 17 to the adjuster screw 14. The number 20 designates a block which is fixed to the frame of the buckle folding machine, or is otherwise held in fixed position. The number 21 designates a lock nut 80 on adjuster screw 14 and the number 22 represents a

2

knob by means of which the adjuster screw may be rotated. A helical compression spring 23 extends between each collar 16 and roller bracket 12.

5 A stationary roller 24 is mounted immediately adjacent to roller 10, and is rotatable on a stationary roller shaft 25. A guide plate 26 which is mounted in fixed position on the machine serves as a support for the incoming blanks, which may be flat sheets of paper, for example. The incoming blanks are fed in the direction indicated by the arrow in Fig. 1. The rollers 10 and/or 25 are mechanically driven by conventional driving means (not shown) and serve as feed means for delivering the blanks into the machine.

15 Adjacent to stationary roller 24 is another adjustable roller 30 which has adjustable mounting means similar to that just described in connection with roller 10. Supported from the machine frame, just above roller 30, are a pair of upper and lower fold plates 31, 32 which are spaced apart from one another to provide a space for 20 receiving the blank coming from between rolls 10, 24. The upper fold plate 31 has, at its inlet end, a lip 33 which has a concave guide face 34 disposed in the path of movement of the blank as it comes from rollers 10, 24. The concave guide face 34 serves to direct the blank toward the inlet between the fold plates 31, 32. Mounted on the fold plates 31, 32, and extending between them, is a stop 35 which is adjustable along the fold plates toward and away from the lip 33. The stop 35 is disposed in the path of movement of the forward edge 25 of the blank as it passes between the upper and lower fold plates 31, 32.

30 Another adjustable roller 40, carried by adjustable mounting means similar to those discussed above, is placed below and immediately adjacent to the roller 30. 35 Upper and lower fold plates 41, 42 (which are similar to fold plates 31, 32) are disposed above the roller 40 in position to receive the blank as it comes from between rollers 30, 24. Between the fold plates 41, 42 is a stop 39. The apparatus also includes another adjustable roller 43 provided with adjustable mounting means and fold plates 44, 45 as heretofore described. Fold plates 44, 45 have a stop 49 between them and are 40 in position to receive the blank as it comes from rollers 30, 40. The number 46 designates a curved guide plate 45 which directs the blank coming from rollers 40, 43 for passage between roller 43 and another adjustably mounted roller 47. Each blank flows from rollers 43, 47 between scoring shafts 50, 50 which carry the processed blanks out of the machine.

40 It will be observed that, in the inlet end of the lip 48 of upper folding plate 44, is a hollow tube 51 which extends transversely across the folding plate 44 from edge to edge, and has a plurality of spaced-apart openings 52 that extend across the folding plate 44 and are directed 55 toward the roller 40. Connected to the tube 51 is a pipe or other conductor 53 leading from a compressor 54 which is driven by a motor 55. It will be understood that air or other fluid under pressure is thereby caused to flow from compressor 54 through conductor 53 into tube 51, and is directed from tube 51 through openings 52 toward the roller 40.

50 From the foregoing description, the operation of the machine will be apparent. As indicated in Fig. 3, the blank which passes between the rollers 10, 24 passes between fold plates 31, 32 and its leading edge is stopped by stop element 35. The continued feed due to rotation of rollers 10, 24 causes the blank to buckle in the area between the fold plates and the rollers 10, 24, 30. The buckled blank is gripped between the rollers 24, 30, thereby forming the fold D and gate C. The blank is then driven by rollers 24, 30 (one or both of which may be rotated by suitable drive means, not shown) between the fold plates 41, 42 where it is similarly buckled with formation of the fold E and gate C' between the rollers 30, 40. At this stage, the blank comprises a flat body portion which has gates C, C' at each end. As shown, the free end edges F, F' of the gates C, C' are immediately adjacent to one another.

55 The gate folded blank coming from between rollers 30, 40 passes through the fluid jet coming from tube 51 between the fold plates 44, 45 and the folded edge E

3

contacts the stop 49. This causes the body portion of the blank to buckle at its center, the movement of the blank being substantially as shown in Fig. 3 and particularly Figs. 4 and 5 of the drawings. It will be observed that, during the formation of the buckle in the body portion of the blank the free end F of the gate C tends to be separated from the body portion of the blank. However, as indicated in Fig. 6, further movement of the buckled portion toward the space between rollers 40, 10 43 brings the end edge F of gate C into the path of the fluid jet coming from tube 51. As shown in Fig. 6, the jet forces the end edge F of gate C against the body portion of the blank and maintains it firmly and uniformly against the blank as it passes between the rollers 40, 43 which form the central fold B.

From Fig. 5 it will be appreciated that, without the air stream coming from tube 51, the end edge F of gate C would tend to separate from the body portion of the blank as the central fold B is formed. This would tend to result in the formation of an undesired fold in the gate itself, or even in a wrinkling or mutilation of the gate. This danger is eliminated by the apparatus and method of this invention wherein one or both gates, and particularly the free end edges thereof, are continuously urged against the body portion of the blank as the central fold is formed.

While we have shown in the drawings one specific embodiment of the invention wherein fluid jet means operate in combination with buckle folding means, it will be appreciated that many objects and advantages of the invention are achieved by the use of such fluid jet means in combination with folding machines of other kinds, as for example knife folding machines.

It will also be appreciated that, while the invention has been described with reference to the production of a gate folded blank with the gate tucked in, it is likewise applicable to the production of a blank like the blank shown in Fig. 2 of the drawings without the central fold B. Other blanks having one or more gates of like or different character may also be produced in accordance with this invention.

While we have selected one embodiment of the invention for illustration in the drawings, it will be appreciated that equivalent elements may be substituted, that parts may be reversed, and that certain features of the invention may be used independently of other features,

all within the spirit and scope of the invention as defined in the appended claim.

Having thus described our invention, we claim:

5 In a machine for forming a blank comprising a body portion having a central fold with a gate at each end, each gate being folded back against the same face of said body portion and having a free end adjacent to said central fold, said free ends of said gates being spaced from one another when said gates are flat against said body portion, the combination of means for sequentially folding the gate portions against said body portion of the folded blank, said folding means including a pair of rollers for feeding the blank, a pair of spaced-apart upper and lower fold plates spaced from 10 said feed rollers to receive the blank, guide means carried by said upper fold plate for guiding said folded blank between edges of said upper and lower fold plates, stop means carried by and extending between said fold plates coacting with the feed means for buckling the body portion of said blank in the zone of said gate ends, 15 a pair of buckle creasing rollers adjacent said edges of the fold plates forming a generally wedge shaped cavity having its open end facing said fold plate edges, said buckle creasing rollers being arranged for folding the body portion of the buckled blank along a line adjacent the free ends of said gates, and pneumatic means including a pressure container carried by and extending transversely across the upper fold plate and also including means for supplying air under pressure continuously to said pressure container, said pressure container having aperture means extending across the fold plate arranged to direct an air stream directly into said wedge shaped cavity against said ends of said gates to maintain said free ends of said gates against said body portion and said body portion against said buckle creasing rollers during the folding operation.
